US008920182B2

(12) **United States Patent**
Montena

(10) **Patent No.:** **US 8,920,182 B2**
(b5) **Date of Patent:** **Dec. 30, 2014**

(54) **CONNECTOR HAVING A COUPLER-BODY
CONTINUITY MEMBER**

(71) Applicant: **PPC Broadband, Inc.**, East Syracuse, NY (US)

(72) Inventor: **Noah P. Montena**, Syracuse, NY (US)

(73) Assignee: **PPC Broadband, Inc.**, East Syracuse, NY (US)

(*) Notice: Subject to any disclaimer, the term of this patent is extended or adjusted under 35 U.S.C. 154(b) by 0 days.

(21) Appl. No.: **14/092,103**

(22) Filed: **Nov. 27, 2013**

(65) **Prior Publication Data**

US 2014/0087578 A1 Mar. 27, 2014

Related U.S. Application Data

(63) Continuation of application No. 13/712,470, filed on Dec. 12, 2012, which is a continuation of application No. 13/016,114, filed on Jan. 28, 2011, now Pat. No. 8,337,229.

(60) Provisional application No. 61/412,611, filed on Nov. 11, 2010.

(57) **ABSTRACT**

A connector having a coupler-body continuity member is provided, wherein the coupler-body continuity member electrically couples a coupler and a body, thereby establishing electrical continuity between the coupler and the body. Furthermore, the coupler-body continuity member facilitates grounding through the connector, and renders an electromagnetic shield preventing ingress of unwanted environmental noise.

PRIORITY CLAIM

This application is a continuation of, and claims the benefit and priority of, U.S. patent application Ser. No. 13/712,470, filed on Dec. 12, 2012, which is a continuation of, and claims the benefit and priority of, U.S. patent application Ser. No. 13/016,114, filed on Jan. 28, 2011, now U.S. Pat. No. 8,337,229 B2, which is a non-provisional of, and claims the benefit and priority of, U.S. Provisional Patent Application Ser. No. 61/412,611 filed on Nov. 11, 2010. The entire contents of such applications are hereby incorporated by reference.

CROSS REFERENCE TO RELATED APPLICATIONS

This application is related to the following commonly-owned, co-pending patent applications: (a) U.S. patent application Ser. No. 14/091,875, filed on Nov. 27, 2013; (b) U.S. patent application Ser. No. 14/092,003, filed on Nov. 27, 2013; (c) U.S. patent application Ser. No. 13/971,147 filed on Aug. 20, 2013; (d) U.S. patent application Ser. No. 13/913,043 filed on Jun. 7, 2013; and (e) U.S. patent application Ser. No. 13/758,586 filed on Feb. 4, 2013.

FIELD OF TECHNOLOGY

The following disclosure relates generally to the field of connectors for coaxial cables. More particularly, to embodiments of a coaxial cable connector having a continuity member that extends electrical continuity through the connector.

BACKGROUND

Broadband communications have become an increasingly prevalent form of electromagnetic information exchange and coaxial cables are common conduits for transmission of broadband communications. Connectors for coaxial cables are typically connected onto complementary interface ports to electrically integrate coaxial cables to various electronic devices. In addition, connectors are often utilized to connect coaxial cables to various communications modifying equipment such as signal splitters, cable line extenders and cable network modules.

To help prevent the introduction of electromagnetic interference, coaxial cables are provided with an outer conductive shield. In an attempt to further screen ingress of environmental noise, typical connectors are generally configured to contact with and electrically extend the conductive shield of attached coaxial cables. Moreover, electromagnetic noise can be problematic when it is introduced via the connective junction between an interface port and a connector. Such problematic noise interference is disruptive where an electromagnetic buffer is not provided by an adequate electrical and/or physical interface between the port and the connector.

Accordingly, there is a need in the field of coaxial cable connectors for an improved connector design.

SUMMARY

The present invention provides an apparatus for use with coaxial cable connections that offers improved reliability.

A first general aspect relates generally to a coaxial cable connector comprising a connector body attached to a post, wherein the connector body has a first end and a second end,

a port coupling element rotatable about the post, the port coupling element separated from the connector body by a distance, and a continuity element positioned between the port coupling element and the connector body proximate the second end of the connector body, wherein the continuity element establishes and maintains electrical continuity between the connector body and the port coupling element.

A second general aspect relates generally to a coaxial cable connector comprising a connector body attached to a post, the connector body having a first end and a second end, wherein the connector body includes an annular outer recess proximate the second end, a port coupling element rotatable about the post, wherein the port coupling element has an internal lip, and a continuity element having a first surface axially separated from a second surface, the first surface contacting the internal lip of the port coupling element and the second surface contacting the outer annular recess of the connector body, wherein the continuity element facilitates grounding of a coaxial cable through the connector.

A third general aspect relates generally to a coaxial cable connector comprising a connector body attached to a post, the connector body having a first end and opposing second end, wherein the connector body includes an annular outer recess proximate the second end, a port coupling element rotatable about the post, wherein the port coupling element has an internal lip, and a means for establishing and maintaining physical and electrical communication between the connector body and the port coupling element.

A fourth general aspect relates generally to a coaxial cable connector comprising a connector body attached to a post, the connector body having a first end and a second end, wherein the connector body includes an annular outer recess proximate the second end, a port coupling element rotatable about the post, wherein the port coupling element has an inner surface, and a continuity element having a first surface and a second surface, the first surface contacting the inner surface of the port coupling element and the second surface contacting the outer annular recess of the connector body, wherein the continuity element establishes and maintains electrical communication between the port coupling element and the connector body in a radial direction.

A fifth general aspect relates generally to a method for facilitating grounding of a coaxial cable through the connector, comprising providing a coaxial cable connector, the coaxial cable connector including: a connector body attached to a post, wherein the connector body has a first end and a second end, and a port coupling element rotatable about the post, the port coupling element separated from the connector body by a distance; and disposing a continuity element positioned between the port coupling element and the connector body proximate the second end of the connector body, wherein the continuity element establishes and maintains electrical continuity between the connector body and the port coupling element.

The foregoing and other features of the invention will be apparent from the following more particular description of various embodiments of the invention.

60 BRIEF DESCRIPTION OF THE DRAWINGS

Some of the embodiments of this invention will be described in detail, with reference to the following figures, wherein like designations denote like members, wherein:

FIG. 1 depicts an exploded perspective view of an embodiment of a connector having a first embodiment of a nut-body continuity element.

FIG. 2A depicts a first side view of a first embodiment of a nut-body continuity element.

FIG. 2B depicts a second side view of a first embodiment of a nut-body continuity element.

FIG. 2C depicts a front view of a first embodiment of a nut-body continuity element.

FIG. 3 depicts a sectional side view of an embodiment of a connector having a first embodiment of a nut-body continuity element.

FIG. 4 depicts a sectional side view of an embodiment of a connector having a first embodiment of a nut-body continuity element and a conductive element.

FIG. 5 depicts a sectional side view of an embodiment of a connector having a first embodiment of a nut-body continuity element inboard of a conductive element.

FIG. 6 depicts a sectional side view of an embodiment of a nut.

FIG. 7 depicts a sectional side view of an embodiment of a post.

FIG. 8 depicts a sectional side view of an embodiment of a connector body.

FIG. 9 depicts a sectional side view of an embodiment of a fastener member.

FIG. 10 depicts a sectional side view of an embodiment of a connector body having an integral post.

FIG. 11 depicts a sectional side view of an embodiment of a connector configured having a first embodiment of a nut-body continuity element with more than one continuity element proximate a second end of a post.

FIG. 12 depicts a sectional side view of an embodiment of a connector configured with a conductive member proximate a second end of a connector body, and a first embodiment of a nut-body continuity element.

FIG. 13 depicts a perspective cut away view of an embodiment of a connector having a second embodiment of a nut-body continuity element.

FIG. 14 depicts a perspective view of a second embodiment of a nut-body continuity element.

FIG. 15 depicts a front view of a second embodiment of a nut-body continuity element.

FIG. 16 depicts a cross-sectional end view of an embodiment of a connector having a second embodiment of a nut-body continuity element.

DETAILED DESCRIPTION OF DRAWINGS

Although certain embodiments of the present invention will be shown and described in detail, it should be understood that various changes and modifications may be made without departing from the scope of the appended claims. The scope of the present invention will in no way be limited to the number of constituting components, the materials thereof, the shapes thereof, the relative arrangement thereof, etc., and are disclosed simply as an example of an embodiment. The features and advantages of the present invention are illustrated in detail in the accompanying drawings, wherein like reference numerals refer to like elements throughout the drawings.

As a preface to the detailed description, it should be noted that, as used in this specification and the appended claims, the singular forms "a", "an" and "the" include plural referents, unless the context clearly dictates otherwise.

Referring to the drawings, FIG. 1 depicts one embodiment of a connector 100. The connector 100 may include a coaxial cable 10 having a protective outer jacket 12, a conductive grounding shield 14 or shields 14, an interior dielectric 16 (potentially surrounded by a conductive foil layer 15), and a center conductor 18. The coaxial cable 10 may be prepared by

removing the protective outer jacket 12 and drawing back the conductive grounding shield 14 to expose a portion of the interior dielectric 16 (potentially surrounded by a conductive foil layer 15). Further preparation of the embodied coaxial cable 10 may include stripping the dielectric 16 (and potential conductive foil layer 15) to expose a portion of the center conductor 18. The protective outer jacket 12 is intended to protect the various components of the coaxial cable 10 from damage which may result from exposure to dirt or moisture and from corrosion. Moreover, the protective outer jacket 12 may serve in some measure to secure the various components of the coaxial cable 10 in a contained cable design that protects the cable 10 from damage related to movement during cable installation. The conductive grounding shield 14 may be comprised of conductive materials suitable for providing an electrical ground connection. Various embodiments of the shield 14 may be employed to screen unwanted noise. For instance, the shield 14 may comprise several conductive strands formed in a continuous braid around the dielectric 16 (potentially surrounding a conductive foil layer 15). Combinations of foil and/or braided strands may be utilized wherein the conductive shield 14 may comprise a foil layer, then a braided layer, and then a foil layer. Those in the art will appreciate that various layer combinations may be implemented in order for the conductive grounding shield 14 to effectuate an electromagnetic buffer helping to prevent ingress of environmental noise that may disrupt broadband communications. Furthermore, there may be more than one grounding shield 14, such as a tri-shield or quad shield cable, and there may also be flooding compounds protecting the shield 14. The dielectric 16 may be comprised of materials suitable for electrical insulation. It should be noted that the various materials of which all the various components of the coaxial cable 10 are comprised should have some degree of elasticity allowing the cable 10 to flex or bend in accordance with traditional broadband communications standards, installation methods and/or equipment. It should further be recognized that the radial thickness of the coaxial cable 10, protective outer jacket 12, conductive grounding shield 14, interior dielectric 16 and/or center conductor 18 may vary based upon generally recognized parameters corresponding to broadband communication standards and/or equipment.

The conductive foil layer 15 may comprise a layer of foil wrapped or otherwise positioned around the dielectric 16, thus the conductive foil layer 15 may surround and/or encompass the dielectric 16. For instance, the conductive foil layer 15 may be positioned between the dielectric 16 and the shield 14. In one embodiment, the conductive foil layer 15 may be bonded to the dielectric 16. In another embodiment, the conductive foil layer 15 may be generally wrapped around the dielectric 16. The conductive foil layer 15 may provide a continuous uniform outer conductor for maintaining the coaxial condition of the coaxial cable 10 along its axial length. The coaxial cable 10 having, inter alia, a conductive foil layer 15 may be manufactured in thousands of feet of lengths. Furthermore, the conductive foil layer 15 may be manufactured to a nominal outside diameter with a plus minus tolerance on the diameter, and may be a wider range than what may normally be achievable with machined, molded, or cast components. The outside diameter of the conductive foil layer 15 may vary in dimension down the length of the cable 10, thus its size may be unpredictable at any point along the cable 10. Due to this unpredictability, the contact between the post 40 and the conductive foil layer 15 may not be sufficient or adequate for conductivity or continuity throughout the connector 100. Thus, a nut-body continuity element 75 may be placed between the nut 30 and the

connector body 50 to allow continuity and/or continuous physical and electrical contact or communication between the nut 30 and the connector body 50. Continuous conductive and electrical continuity between the nut 30 and the connector body 50 can be established by the physical and electrical contact between the connector body 50 and the nut-body continuity element 75, wherein the nut-body continuity element 75 is simultaneously in physical and electrical contact with the nut 30. While operably configured, electrical continuity may be established and maintained throughout the connector 100 and to interface port 20 via the conductive foil layer 15 which contacts the conductive grounding shield 14, which contacts the connector body 50, which contacts the nut-body continuity element 75, which contacts the nut 30, the nut 30 being advanced onto interface port 20. Alternatively, electrical continuity can be established and maintained throughout the connector 100 via the conductive foil layer 15, which contacts the post 40, which contacts the connector body 50, which contacts the nut-body continuity element 75, which contacts the nut 30, the nut 30 being advanced onto interface port 20.

Referring further to FIG. 1, the connector 100 may make contact with a coaxial cable interface port 20. The coaxial cable interface port 20 includes a conductive receptacle 22 for receiving a portion of a coaxial cable center conductor 18 sufficient to make adequate electrical contact. The coaxial cable interface port 20 may further comprise a threaded exterior surface 24. However, various embodiments may employ a smooth surface, as opposed to threaded exterior surface. In addition, the coaxial cable interface port 20 may comprise a mating edge 26. It should be recognized that the radial thickness and/or the length of the coaxial cable interface port 20 and/or the conductive receptacle 22 may vary based upon generally recognized parameters corresponding to broadband communication standards and/or equipment. Moreover, the pitch and height of threads which may be formed upon the threaded exterior surface 24 of the coaxial cable interface port 20 may also vary based upon generally recognized parameters corresponding to broadband communication standards and/or equipment. Furthermore, it should be noted that the interface port 20 may be formed of a single conductive material, multiple conductive materials, or may be configured with both conductive and non-conductive materials corresponding to the port's 20 electrical interface with a connector 100. For example, the threaded exterior surface may be fabricated from a conductive material, while the material comprising the mating edge 26 may be non-conductive or vice versa. However, the conductive receptacle 22 should be formed of a conductive material. Further still, it will be understood by those of ordinary skill that the interface port 20 may be embodied by a connective interface component of a communications modifying device such as a signal splitter, a cable line extender, a cable network module and/or the like.

With continued reference to FIG. 1, an embodiment of the connector 100 may further comprise a nut 30, a post 40, a connector body 50, a fastener member 60, and a nut-body continuity element 75. The nut-body continuity element 75 should be formed of a conductive material. Such conductive materials may include, but are not limited to conductive polymers, conductive plastics, conductive elastomers, conductive elastomeric mixtures, composite materials having conductive properties, metal, soft metals, conductive rubber, and/or the like and/or any operable combination thereof. The nut-body continuity element 75 may be resilient, flexible, elastic, etc., or may be rigid and/or semi-rigid. The nut-body continuity element 75 may have a circular, rectangular, square, or any appropriate geometrically dimensioned cross-section. For

example, the nut-body continuity element 75 may have a flat rectangular cross-section similar to a metal washer or wave washer. The nut-body continuity element 75 may also be a conductive element, conductive member, continuity element, a conductive ring, a conductive wave ring, a continuity ring, a continuity wave ring, a resilient member, and the like.

Referring to the drawings, FIGS. 2A-2C depict further embodiments of a nut-body continuity element 75, specifically, embodiments of a structure and/or design of a nut-body continuity element 75. For example, the nut-body continuity element 75 may comprise a substantially circinate torus or toroid structure. Moreover, nut-body continuity element 75 may have a slight bend to provide axial separation between contact points. For instance, the point on first surface 71 of the nut-body continuity element 75 contacting the nut 30 may be an axial distance, d_1 , away from the point on the second surface 72 of the nut-body continuity element 75 contacting the connector body 50. To facilitate contact with the connector body 50 and with the nut 30, the nut-body continuity element 75 may have one or more bumps 73 located on the surface of the nut-body continuity element 75. Bumps 73 may be any protrusion from the surface of the nut-body continuity element 75 that can facilitate the contact of the nut 30 and the connector body 50. The surface of the nut-body continuity element 75 can comprise a first surface 71 and a second surface 72; bumps 73 may be located on both the first surface 71 of the nut-body continuity element 75 and the second surface 72 of the nut-body continuity element 75, or just one of the first surface 71 or second surface 72. In some embodiments, the nut-body continuity element 75 does not have any bumps 73 positioned on the surface, and relies on smooth, flat contact offered by the first surface 71 and/or second surface 72. Because of the shape and design of the nut-body continuity element 75 (i.e. because of the bended configuration), the nut-body continuity element 75 should make contact with the nut 30 at two or more points along the first surface 71, and should also make contact with the connector body 50 at two or more points along the second surface 72. Depending on the angle of curvature of the bend, the nut-body continuity element 75 may contact the nut 30 and the connector body 50 at multiple or single locations along the first surface 71 and second surface 72 of the nut-body continuity element 75. The angle of curvature of the bend of the nut-body continuity element 75 may vary, including a nut-body continuity element 75 with little to no axial separation.

Furthermore, a bended configuration of the nut-body continuity element 75 can allow a portion of the nut-body continuity element 75 to physically contact the nut 30 and another portion of the nut-body continuity element 75 to contact the connector body 50 in a biasing relationship. For instance, the bend in the nut-body continuity element 75 can allow deflection of the element when subjected to an external force, such as a force exerted by the nut 30 (e.g. internal lip 36) or the connector body 50 (e.g. outer annular recess 56). The biasing relationship between the nut 30, the connector body 50, and the nut-body continuity element 75, evidenced by the deflection of the nut-body continuity element 75, establishes and maintains constant contact between the nut 30, the connector body 50, and the nut-body continuity element 75. The constant contact may establish and maintain electrical continuity through a connector 100. A bend in the nut-body continuity element 75 may also be a wave, a compression, a deflection, a contour, a bow, a curve, a warp, a deformation, and the like. Those skilled in the art should appreciate the various resilient shapes and variants of elements the nut-body continuity ele-

ment 75 may encompass to establish and maintain electrical communication between the nut 30 and the connector body 50.

Referring still to the drawings, FIG. 3 depicts an embodiment of a connector 100 having a nut-body continuity element 75. The nut-body continuity element 75 may be disposed and/or placed between the nut 30 and the connector body 50. For example, the nut-body continuity element 75 may be configured to cooperate with the annular recess 56 proximate the second end 54 of connector body 50 and the cavity 38 extending axially from the edge of second end 34 and partially defined and bounded by an outer internal wall 39 of threaded nut 30 (see FIG. 6) such that the continuity element 75 may make contact with and/or reside contiguous with the annular recess 56 of connector body 50 and may make contact with and/or reside contiguous with the mating edge 37 of threaded nut 30. Moreover, a portion of the nut-body continuity element 75 can reside inside and/or contact the cavity 38 proximate an end 32 of the nut, while another portion of the same nut-body continuity element 75 contacts an outer annular recess 56 proximate the second end 54. Alternatively, the nut-body continuity element 75 may have a radial relationship with the post 40, proximate the second 44 of the post 40. For example, the nut-body continuity element 75 may be radially disposed a distance above the post 40. However, the placement of the nut-body continuity element 75 in all embodiments does not restrict or prevent the nut 30 (port coupling element) from freely rotating, in particular, rotating about the stationary post 40. In some embodiments, the nut-body continuity element 75 may be configured to rotate or spin with the nut 30, or against the nut 30. In many embodiments, the nut-body continuity element 75 is stationary with respect to the nut 30. In other embodiments, the nut-body continuity element 75 may be press-fit into position between the nut 30 and the connector body 50. Furthermore, those skilled in the art would appreciate that the nut-body continuity element 75 may be fabricated by extruding, coating, molding, injecting, cutting, turning, elastomeric batch processing, vulcanizing, mixing, stamping, casting, and/or the like and/or any combination thereof in order to provide efficient production of the component.

Furthermore, the nut-body continuity element 75 need not be radially disposed 360° around the post 40, or extend, reside contiguous, etc., 360° around the outer annular recess 56 or cavity 38. For example, the nut-body continuity element 75 may be radially disposed only a portion of 360° around the outer annular recess 56 or cavity 38. Specifically, the nut-body continuity element 75 may be formed in the shape of a half circle, crescent, half moon, semi-circle, C-shaped, and the like. As long as the nut-body continuity element 75 physically contacts the nut 30 and the connector body 50, physical and electrical continuity may be established and maintained. In a semi-circular embodiment of the nut-body continuity element 75, the first surface 71 of the nut-body continuity element 75 can physically contact the internal lip 36 of nut 30 at least once, while simultaneously contacting the outer annular recess 56 of the connector body 50 at least once. Thus, electrical continuity between the connector body 50 and the nut 30 may be established and maintained by implementation of various embodiments of the nut-body continuity element 75.

For instance, through various implementations of embodiments of the nut-body continuity element 75, physical and electrical communication or contact between the nut 30 and the nut-body continuity element 75, wherein the nut-body continuity element 75 simultaneously contacts the connector body 50 may help transfer the electricity or current from the

post 40 (i.e. through conductive communication of the grounding shield 14) to the nut 30 and to the connector body 50, which may ground the coaxial cable 10 when the nut 30 is in electrical or conductive communication with the coaxial cable interface port 20. In many embodiments, the nut-body continuity element 75 axially contacts the nut 30 and the connector body 50. In other embodiments, the nut-body continuity element 75 radially contacts the nut 30 and the connector body 50.

FIG. 4 depicts an embodiment of the connector 100 which may comprise a nut 30, a post 40, a connector body 50, a fastener member 60, a nut-body continuity element 75, and a connector body conductive member 80 proximate the second end 54 of the connector body 50. The nut-body continuity element 75 may reside in additional cavity 35 proximate the end 32 of the nut 30 and additional annular recess 53 proximate the second end 54 of the connector body 50. The connector body conductive member 80 should be formed of a conductive material. Such materials may include, but are not limited to conductive polymers, plastics, elastomeric mixtures, composite materials having conductive properties, soft metals, conductive rubber, and/or the like and/or any workable combination thereof. The connector body conductive member 80 may comprise a substantially circinate torus or toroid structure, or other ring-like structure. For example, an embodiment of the connector body conductive member 80 may be an O-ring configured to cooperate with the annular recess 56 proximate the second end 54 of connector body 50 and the cavity 38 extending axially from the edge of second end 34 and partially defined and bounded by an outer internal wall 39 of threaded nut 30 (see FIG. 6) such that the connector body conductive O-ring 80 may make contact with and/or reside contiguous with the annular recess 56 of connector body 50 and outer internal wall 39 of threaded nut 30 when operably attached to post 40 of connector 100. The connector body conductive member 80 may facilitate an annular seal between the threaded nut 30 and connector body 50 thereby providing a physical barrier to unwanted ingress of moisture and/or other environmental contaminants. Moreover, the connector body conductive member 80 may further facilitate electrical coupling of the connector body 50 and threaded nut 30 by extending therebetween an unbroken electrical circuit. In addition, the connector body conductive member 80 may facilitate grounding of the connector 100, and attached coaxial cable (shown in FIG. 1), by extending the electrical connection between the connector body 50 and the threaded nut 30. Furthermore, the connector body conductive member 80 may effectuate a buffer preventing ingress of electromagnetic noise between the threaded nut 30 and the connector body 50. It should be recognized by those skilled in the relevant art that the connector body conductive member 80 may be manufactured by extruding, coating, molding, injecting, cutting, turning, elastomeric batch processing, vulcanizing, mixing, stamping, casting, and/or the like and/or any combination thereof in order to provide efficient production of the component. Therefore, the combination of the connector body conductive member 80 and the nut-body continuity element 75 may further electrically couple the nut 30 and the connector body 50 to establish and maintain electrical continuity throughout connector 100. However, the positioning and location of these components may swap. For instance, FIG. 5 depicts an embodiment of a connector 100 having a nut-body continuity element 75 inboard of connector body conductive member 80.

With additional reference to the drawings, FIG. 6 depicts a sectional side view of an embodiment of a nut 30 having an end 32 and opposing second end 34. The nut 30 (or port

coupling element, coupling element, coupler) may be rotatably secured to the post 40 to allow for rotational movement about the post 40. The nut 30 may comprise an internal lip 36 located proximate the second end 34 and configured to hinder axial movement of the post 40 (shown in FIG. 7). The lip 36 may include a mating edge 37 which may contact the post 40 while connector 100 is operably configured. Furthermore, the threaded nut 30 may comprise a cavity 38 extending axially from the edge of second end 34 and partially defined and bounded by the internal lip 36. The cavity 38 may also be partially defined and bounded by an outer internal wall 39. The threaded nut 30 may be formed of conductive materials facilitating grounding through the nut 30. Accordingly the nut 30 may be configured to extend an electromagnetic buffer by electrically contacting conductive surfaces of an interface port 20 when a connector 100 (shown in FIG. 3) is advanced onto the port 20. In addition, the threaded nut 30 may be formed of non-conductive material and function only to physically secure and advance a connector 100 onto an interface port 20. Moreover, the threaded nut 30 may be formed of both conductive and non-conductive materials. For example the internal lip 36 may be formed of a polymer, while the remainder of the nut 30 may be comprised of a metal or other conductive material. In addition, the threaded nut 30 may be formed of metals or polymers or other materials that would facilitate a rigidly formed body. Manufacture of the threaded nut 30 may include casting, extruding, cutting, turning, tapping, drilling, injection molding, blow molding, or other fabrication methods that may provide efficient production of the component. Those in the art should appreciate the various embodiments of the nut 30 may also comprise a coupler member having no threads, but being dimensioned for operable connection to a corresponding to an interface port, such as interface port 20.

Additionally, nut 30 may contain an additional cavity 35, formed similarly to cavity 38. In some embodiments that include an additional cavity 35, a secondary internal lip 33 should be formed to provide a surface for the contact and/or interference with the nut-body continuity element 75. For example, the nut-body continuity element 75 may be configured to cooperate with the additional annular recess 53 proximate the second end 54 of connector body 50 and the additional cavity 35 extending axially from the edge of second end 34 and partially defined and bounded by the secondary internal lip 33 of threaded nut 30 (see FIGS. 5-6) such that the nut-body continuity element 75 may make contact with and/or reside contiguous with the additional annular recess 53 of connector body 50 and the secondary internal lip 33 of threaded nut 30 (see FIG. 4). In some embodiments, there may be an additional recess, 35, and 53; however, the nut-body continuity element 75 may be positioned as embodied in FIG. 5.

With further reference to the drawings, FIG. 7 depicts a sectional side view of an embodiment of a post 40 in accordance with the present invention. The post 40 may comprise a first end 42 and opposing second end 44. Furthermore, the post 40 may comprise a flange 46 operably configured to contact internal lip 36 of threaded nut 30 (shown in FIG. 6) thereby facilitating the prevention of axial movement of the post beyond the contacted internal lip 36. Further still, an embodiment of the post 40 may include a surface feature 48 such as a shallow recess, detent, cut, slot, or trough. Additionally, the post 40 may include a mating edge 49. The mating edge 49 may be configured to make physical and/or electrical contact with an interface port 20 or mating edge member (shown in FIG. 1) or O-ring 70 (shown in FIGS. 11-12). The post 40 should be formed such that portions of a

prepared coaxial cable 10 including the dielectric 16, conductive foil layer 15, and center conductor 18 (shown in FIGS. 1 and 2) may pass axially into the first end 42 and/or through the body of the post 40. Moreover, the post 40 should be dimensioned such that the post 40 may be inserted into an end of the prepared coaxial cable 10, around the conductive foil layer surrounding the dielectric 16, and under the protective outer jacket 12 and conductive grounding shield 14. Accordingly, where an embodiment of the post 40 may be inserted into an end of the prepared coaxial cable 10 under the drawn back conductive grounding shield 14 substantial physical and/or electrical contact with the shield 14 may be accomplished thereby facilitating grounding through the post 40. The post 40 may be formed of metals or other conductive materials that would facilitate a rigidly formed body. In addition, the post 40 may also be formed of non-conductive materials such as polymers or composites that facilitate a rigidly formed body. In further addition, the post may be formed of a combination of both conductive and non-conductive materials. For example, a metal coating or layer may be applied to a polymer or other non-conductive material. Manufacture of the post 40 may include casting, extruding, cutting, turning, drilling, injection molding, spraying, blow molding, or other fabrication methods that may provide efficient production of the component.

With continued reference to the drawings, FIG. 8 depicts a sectional side view of a connector body 50. The connector body 50 may comprise a first end 52 and opposing second end 54. Moreover, the connector body 50 may include an internal annular lip 55 configured to mate and achieve purchase with the surface feature 48 of post 40 (shown in FIG. 7). In addition, the connector body 50 may include an outer annular recess 56 located proximate the second end 54. Furthermore, the connector body may include a semi-rigid, yet compliant outer surface 57, wherein the surface 57 may include an annular detent 58. The outer surface 57 may be configured to form an annular seal when the first end 52 is deformably compressed against a received coaxial cable 10 by a fastener member 60 (shown in FIG. 3). Further still, the connector body 50 may include internal surface features 59, such as annular serrations formed proximate the first end 52 of the connector body 50 and configured to enhance frictional restraint and gripping of an inserted and received coaxial cable 10. The connector body 50 may be formed of materials such as, polymers, bendable metals or composite materials that facilitate a semi-rigid, yet compliant surface 57. Further, the connector body 50 should be formed of conductive materials, or a combination of conductive and non-conductive materials such that electrical continuity can be established between the connector body 50 and the nut 30, facilitated by the nut-body continuity element 75. Manufacture of the connector body 50 may include casting, extruding, cutting, turning, drilling, injection molding, spraying, blow molding, or other fabrication methods that may provide efficient production of the component.

Additionally, the connector body 50 may contain an additional annular recess 53, formed similarly to outer annular recess 56. In some embodiments, the additional annular recess 53 may provide a surface for the contact and/or interference with the nut-body continuity element 75. For example, the nut-body continuity element 75 may be configured to cooperate with the additional annular recess 53 proximate the second end 54 of connector body 50 and the additional cavity 35 extending axially from the edge of second end 34 and partially defined and bounded by the secondary internal lip 33 of threaded nut 30 (see FIGS. 5-6) such that the nut-body continuity element 75 may make contact with and/or reside contiguous with the additional annular recess 53 of connector body 50 and the secondary internal lip 33 of threaded nut 30 (see FIG. 4).

11

or reside contiguous with the annular recess 53 of connector body 50 and the secondary internal lip 33 of threaded nut 30 (see FIG. 4). In some embodiments, there may be an additional recess, 35, and 53; however, the nut-body continuity element 75 may be positioned as embodied in FIG. 5.

Referring further to the drawings, FIG. 9 depicts a sectional side view of an embodiment of a fastener member 60 in accordance with the present invention. The fastener member 60 may have a first end 62 and opposing second end 64. In addition, the fastener member 60 may include an internal annular protrusion 63 located proximate the first end 62 of the fastener member 60 and configured to mate and achieve purchase with the annular detent 58 on the outer surface 57 of connector body 50 (shown in FIG. 5). Moreover, the fastener member 60 may comprise a central passageway 65 defined between the first end 62 and second end 64 and extending axially through the fastener member 60. The central passageway 65 may comprise a ramped surface 66 which may be positioned between a first opening or inner bore 67 having a first diameter positioned proximate with the first end 62 of the fastener member 60 and a second opening or inner bore 68 having a second diameter positioned proximate with the second end 64 of the fastener member 60. The ramped surface 66 may act to deformably compress the inner surface 57 of a connector body 50 when the fastener member 60 is operated to secure a coaxial cable 10 (shown in FIG. 3). Additionally, the fastener member 60 may comprise an exterior surface feature 69 positioned proximate with the second end 64 of the fastener member 60. The surface feature 69 may facilitate gripping of the fastener member 60 during operation of the connector 100 (see FIG. 3). Although the surface feature is shown as an annular detent, it may have various shapes and sizes such as a ridge, notch, protrusion, knurling, or other friction or gripping type arrangements. It should be recognized, by those skilled in the requisite art, that the fastener member 60 may be formed of rigid materials such as metals, polymers, composites and the like. Furthermore, the fastener member 60 may be manufactured via casting, extruding, cutting, turning, drilling, injection molding, spraying, blow molding, or other fabrication methods that may provide efficient production of the component.

Referring still further to the drawings, FIG. 10 depicts a sectional side view of an embodiment of an integral post connector body 90 in accordance with the present invention. The integral post connector body 90 may have a first end 91 and opposing second end 92. The integral post connector body 90 physically and functionally integrates post and connector body components of an embodied connector 100 (shown in FIG. 1). Accordingly, the integral post connector body 90 includes a post member 93. The post member 93 may render connector operability similar to the functionality of post 40 (shown in FIG. 7). For example, the post member 93 of integral post connector body 90 may include a mating edge 99 configured to make physical and/or electrical contact with an interface port 20 (shown in FIG. 1) or mating edge member or O-ring 70 (shown in FIGS. 11-12). The post member 93 of integral should be formed such that portions of a prepared coaxial cable 10 including the dielectric 16, conductive foil layer 15, and center conductor 18 (shown in FIG. 1) may pass axially into the first end 91 and/or through the post member 93. Moreover, the post member 93 should be dimensioned such that a portion of the post member 93 may be inserted into an end of the prepared coaxial cable 10, around the dielectric 16 and conductive foil layer 15, and under the protective outer jacket 12 and conductive grounding shield 14 or shields 14. Further, the integral post connector body 90 includes a connector body surface 94. The connector body surface 94 may

12

render connector 100 operability similar to the functionality of connector body 50 (shown in FIG. 8). Hence, inner connector body surface 94 should be semi-rigid, yet compliant. The outer connector body surface 94 may be configured to form an annular seal when compressed against a coaxial cable 10 by a fastener member 60 (shown in FIG. 3). In addition, the integral post connector body 90 may include an interior wall 95. The interior wall 95 may be configured as an unbroken surface between the post member 93 and outer connector body surface 94 of integral post connector body 90 and may provide additional contact points for a conductive grounding shield 14 of a coaxial cable 10. Furthermore, the integral post connector body 90 may include an outer recess formed proximate the second end 92. Further still, the integral post connector body 90 may comprise a flange 97 located proximate the second end 92 and operably configured to contact internal lip 36 of threaded nut 30 (shown in FIG. 6) thereby facilitating the prevention of axial movement of the integral post connector body 90 with respect to the threaded nut 30, yet still allowing rotational movement of the axially secured nut 30. The integral post connector body 90 may be formed of materials such as, polymers, bendable metals or composite materials that facilitate a semi-rigid, yet compliant outer connector body surface 94. Additionally, the integral post connector body 90 may be formed of conductive or non-conductive materials or a combination thereof. Manufacture of the integral post connector body 90 may include casting, extruding, cutting, turning, drilling, injection molding, spraying, blow molding, or other fabrication methods that may provide efficient production of the component.

With continued reference to the drawings, FIG. 11 depicts a sectional side view of an embodiment of a connector 100 configured with a mating edge conductive member 70 proximate a second end 44 of a post 40, and a nut-body continuity element 75 located proximate a second end 54 of the connector body 50, and a connector body conductive member 80 (as described supra). The mating edge conductive member 70 should be formed of a conductive material. Such materials may include, but are not limited to conductive polymers, conductive plastics, conductive elastomers, conductive elastomeric mixtures, composite materials having conductive properties, soft metals, conductive rubber, and/or the like and/or any operable combination thereof. The mating edge conductive member 70 may comprise a substantially circinate torus or toroid structure adapted to fit within the internal threaded portion of threaded nut 30 such that the mating edge conductive member 70 may make contact with and/or reside continuous with a mating edge 49 of a post 40 when operably attached to post 40 of connector 100. For example, one embodiment of the mating edge conductive member 70 may be an O-ring. The mating edge conductive member 70 may facilitate an annular seal between the threaded nut 30 and post 40 thereby providing a physical barrier to unwanted ingress of moisture and/or other environmental contaminates. Moreover, the mating edge conductive member 70 may facilitate electrical coupling of the post 40 and threaded nut 30 by extending therebetween an unbroken electrical circuit. In addition, the mating edge conductive member 70 may facilitate grounding of the connector 100, and attached coaxial cable (shown in FIG. 3), by extending the electrical connection between the post 40 and the threaded nut 30. Furthermore, the mating edge conductive member 70 may effectuate a buffer preventing ingress of electromagnetic noise between the threaded nut 30 and the post 40. The mating edge conductive member or O-ring 70 may be provided to users in an assembled position proximate the second end 44 of post 40, or users may themselves insert the mating edge conductive

O-ring 70 into position prior to installation on an interface port 20 (shown in FIG. 1). Those skilled in the art would appreciate that the mating edge conductive member 70 may be fabricated by extruding, coating, molding, injecting, cutting, turning, elastomeric batch processing, vulcanizing, mixing, stamping, casting, and/or the like and/or any combination thereof in order to provide efficient production of the component. FIG. 12 depicts an embodiment of a connector 100 having a mating edge conductive member 70 proximate a second end 44 of a post 40, and a nut-body continuity element 75 located proximate a second end 54 of the connector body 50, without the presence of connector body conductive member 80.

With reference to the drawings, either one or all three of the nut-body continuity element 75, the mating edge conductive member, or O-ring 70, and connector body conductive member, or O-ring 80, may be utilized in conjunction with an integral post connector body 90. For example, the mating edge conductive member 70 may be inserted within a threaded nut 30 such that it contacts the mating edge 99 of integral post connector body 90 as implemented in an embodiment of connector 100. By further example, the connector body conductive member 80 may be positioned to cooperate and make contact with the recess 96 of connector body 90 and the outer internal wall 39 (see FIG. 6) of an operably attached threaded nut 30 of an embodiment of a connector 100. Those in the art should recognize that embodiments of the connector 100 may employ all three of the nut-body continuity element 75, the mating edge conductive member 70, and the connector body conductive member 80 in a single connector 100 (shown in FIG. 11). Accordingly the various advantages attributable to each of the nut-body continuity element 75, mating edge conductive member 70, and the connector body conductive member 80 may be obtained.

A method for grounding a coaxial cable 10 through a connector 100 is now described with reference to FIG. 3 which depicts a sectional side view of an embodiment of a connector 100. A coaxial cable 10 may be prepared for connector 100 attachment. Preparation of the coaxial cable 10 may involve removing the protective outer jacket 12 and drawing back the conductive grounding shield 14 to expose a portion of a conductive foil layer 15 surrounding the interior dielectric 16. Further preparation of the embodied coaxial cable 10 may include stripping the and dielectric 16 (and potential conductive foil layer 15) to expose a portion of the center conductor 18. Various other preparatory configurations of coaxial cable 10 may be employed for use with connector 100 in accordance with standard broadband communications technology and equipment. For example, the coaxial cable may be prepared without drawing back the conductive grounding shield 14, but merely stripping a portion thereof to expose the interior dielectric 16 (potentially surrounding conductive foil layer 15), and center conductor 18.

Referring again to FIG. 3, further depiction of a method for grounding a coaxial cable 10 through a connector 100 is described. A connector 100 including a post 40 having a first end 42 and second end 44 may be provided. Moreover, the provided connector may include a connector body 50 and a nut-body continuity element 75 located between the nut 30 and the connector body 50. The proximate location of the nut-body continuity element 75 should be such that the nut-body continuity element 75 makes simultaneous physical and electrical contact with the nut 30 and the connector body 50.

Grounding may be further attained and maintained by fixedly attaching the coaxial cable 10 to the connector 100. Attachment may be accomplished by insetting the coaxial cable 10 into the connector 100 such that the first end 42 of

post 40 is inserted under the conductive grounding sheath or shield 14 and around the conductive foil layer 15 potentially encompassing the dielectric 16. Where the post 40 is comprised of conductive material, a grounding connection may be achieved between the received conductive grounding shield 14 of coaxial cable 10 and the inserted post 40. The ground may extend through the post 40 from the first end 42 where initial physical and electrical contact is made with the conductive grounding shield 14 to the second end 44 of the post 40. Once received, the coaxial cable 10 may be securely fixed into position by radially compressing the outer surface 57 of connector body 50 against the coaxial cable 10 thereby affixing the cable into position and sealing the connection. Furthermore, radial compression of a resilient member placed within the connector 100 may attach and/or the coaxial cable 10 to connector 100. In addition, the radial compression of the connector body 50 may be effectuated by physical deformation caused by a fastener member 60 that may compress and lock the connector body 50 into place. Moreover, where the connector body 50 is formed of materials having an elastic limit, compression may be accomplished by crimping tools, or other like means that may be implemented to permanently deform the connector body 50 into a securely affixed position around the coaxial cable 10.

As an additional step, grounding of the coaxial cable 10 through the connector 100 may be accomplished by advancing the connector 100 onto an interface port 20 until a surface of the interface port mates with a surface of the nut 30. Because the nut-body continuity element 75 is located such that it makes physical and electrical contact with the connector body 50, grounding may be extended from the post 40 or conductive foil layer 15 through the conductive grounding shield 14, then through the nut-body continuity element 75 to the nut 30, and then through the mated interface port 20. Accordingly, the interface port 20 should make physical and electrical contact with the nut 30. Advancement of the connector 100 onto the interface port 20 may involve the threading on of attached threaded nut 30 of connector 100 until a surface of the interface port 20 abuts the mating edge 49 of the post (see FIG. 7) and axial progression of the advancing connector 100 is hindered by the abutment. However, it should be recognized that embodiments of the connector 100 may be advanced onto an interface port 20 without threading and involvement of a threaded nut 30. Once advanced until progression is stopped by the conductive contact of the mating edge 49 of the post 40 with interface port 20, the connector 100 may be further shielded from ingress of unwanted electromagnetic interference. Moreover, grounding may be accomplished by physical advancement of various embodiments of the connector 100 wherein a nut-body continuity element 75 facilitates electrical connection of the connector 100 and attached coaxial cable 10 to an interface port 20.

With continued reference to FIG. 11 and additional reference to FIG. 12, further depiction of a method for grounding a coaxial cable 10 through a connector 100 is described. A connector 100 including a post 40 having a first end 42 and second end 44 may be provided. Moreover, the provided connector may include a connector body 50 and a mating edge conductive member 70 located proximate the second end 44 of post 40. The proximate location of the mating edge conductive member 70 should be such that the mating edge conductive member 70 makes physical and electrical contact with post 40. In one embodiment, the mating edge conductive member or O-ring 70 may be inserted into a threaded nut 30 until it abuts the mating edge 49 of post 40. However, other embodiments of connector 100 may locate the mating edge

15

conductive member 70 at or very near the second end 44 of post 40 without insertion of the mating edge conductive member 70 into a threaded nut 30.

Grounding may be further attained by fixedly attaching the coaxial cable 10 to the connector 100. Attachment may be accomplished by insetting the coaxial cable 10 into the connector 100 such that the first end 42 of post 40 is inserted under the conductive grounding sheath or shield 14 and around the conductive foil layer 15 and dielectric 16. Where the post 40 is comprised of conductive material, a grounding connection may be achieved between the received conductive grounding shields 14 of coaxial cable 10 and the inserted post 40. The ground may extend through the post 40 from the first end 42 where initial physical and electrical contact is made with the conductive grounding shield 14 to the mating edge 49 located at the second end 44 of the post 40. Once received, the coaxial cable 10 may be securely fixed into position by radially compressing the outer surface 57 of connector body 50 against the coaxial cable 10 thereby affixing the cable into position and sealing the connection. The radial compression of the connector body 50 may be effectuated by physical deformation caused by a fastener member 60 that may compress and lock the connector body 50 into place. Moreover, where the connector body 50 is formed of materials having an elastic limit, compression may be accomplished by crimping tools, or other like means that may be implemented to permanently deform the connector body 50 into a securely affixed position around the coaxial cable 10.

As an additional step, grounding of the coaxial cable 10 through the connector 100 may be accomplished by advancing the connector 100 onto an interface port 20 until a surface of the interface port mates with the mating edge conductive member 70. Because the mating edge conductive member 70 is located such that it makes physical and electrical contact with post 40, grounding may be extended from the post 40 through the mating edge conductive member 70 and then through the mated interface port 20. Accordingly, the interface port 20 should make physical and electrical contact with the mating edge conductive member 70. The mating edge conductive member 70 may function as a conductive seal when physically pressed against the interface port 20. Advancement of the connector 100 onto the interface port 20 may involve the threading on of attached threaded nut 30 of connector 100 until a surface of the interface port 20 abuts the mating edge conductive member 70 and axial progression of the advancing connector 100 is hindered by the abutment. However, it should be recognized that embodiments of the connector 100 may be advanced onto an interface port 20 without threading and involvement of a threaded nut 30. Once advanced until progression is stopped by the conductive sealing contact of mating edge conductive member 70 with interface port 20, the connector 100 may be shielded from ingress of unwanted electromagnetic interference. Moreover, grounding may be accomplished by physical advancement of various embodiments of the connector 100 wherein a mating edge conductive member 70 facilitates electrical connection of the connector 100 and attached coaxial cable 10 to an interface port 20.

A method for electrically coupling the nut 30 and the connector body 50 is now described with reference to FIGS. 1-16. The method of electrically coupling the nut 30 and the connector body 50 may include the steps of providing a connector body 50 attached to the post 40 wherein the connector body 50 includes a first end 52 and a second end 54, the first end 52 configured to deformably compress against and seal a received coaxial cable 10; a rotatable coupling element 30 attached to the post 40; and a nut-body continuity element

16

75 located between the connector body 50 and the rotatable coupling element 30, proximate the second end 54 of the connector body 50, wherein the nut-body continuity element 75 facilitates the grounding of the coaxial cable 10 by electrically coupling the rotatable coupling element 30 to the connector body 50, and advancing the connector 100 onto an interface port 20.

Another method for providing a coaxial cable connector is now described with references to FIGS. 1-16. The method may comprise the steps of providing a coaxial cable connector including: a connector body 50, 250 attached to a post 40, wherein the connector body 50, 250 has a first end 52 and a second end 54, and a port coupling element 30, 230 rotatable about the post 40, the port coupling element 30, 230 separated from the connector body 50, 250 by a distance; and disposing a continuity element 75, 275 positioned between the port coupling element 30, 230 and the connector body 50, 250; proximate the second end 54 of the connector body 50, 250; wherein the continuity element 75, 275 establishes and maintains electrical continuity between the connector body 50, 250 and the port coupling element 30, 230.

Referring now specifically to FIGS. 13-16, connector 200 may include a nut-body continuity element 275 placed between the nut 230 and the connector body 250 to allow continuity and/or continuous physical and electrical contact or communication between the nut 230 and the connector body 250 in the radial direction. Embodiments of connector 200 may include a connector body 250 attached to a post 240, the connector body 250 having a first end and a second end, wherein the connector body 250 includes an annular outer recess proximate the second end, a port coupling element 230 rotatable about the post 240, wherein the port coupling element 230 has an inner surface, and a continuity element 275 having a first surface 271 and a second surface 272, the first surface 271 contacting the inner surface of the port coupling element 230 and the second surface 272 contacting the outer annular recess of the connector body 250, wherein the continuity element 275 establishes and maintains electrical communication between the port coupling element 230 and the connector body 250 in a radial direction. Moreover, continuous conductive and electrical continuity between the nut 230 and the connector body 250 in the radial direction can be established by the physical and electrical contact between the connector body 250 and the nut-body continuity element 275, wherein the nut-body continuity element 275 is simultaneously in physical and electrical contact with the nut 230. Moreover, nut-body continuity element 275 may have a slight bend to provide radial separation between contact points. For instance, the point on first surface 271 of the nut-body continuity element 275 contacting the nut 230 may be of a longer radial distance, r_1 , from the center conductor than the radial distance, r_2 , of the point on the second surface 272 of the nut-body continuity element 275 contacting the connector body 250. In other words, the nut-body continuity element 275 may be an elliptical shape, wherein there is a major radius and a minor radius. The major radius, being larger than the minor radius, is the distance between a center of the nut-body continuity element 275 and the point where the nut-body continuity element 275 contacts the inner surface diameter of the nut 230 (i.e. internal wall 239 of nut 230). The minor radius, being smaller than the major radius, is the distance between the center of the nut-body continuity element 275 and the point where the nut-body continuity element 275 contacts the outer surface diameter of the connector body 250. Therefore, nut-body continuity element 275 may physi-

cally and electrically contact both the nut 230 and the connector body 250, despite the radial separation between the two components.

While this invention has been described in conjunction with the specific embodiments outlined above, it is evident that many alternatives, modifications and variations will be apparent to those skilled in the art. Accordingly, the embodiments of the invention as set forth above are intended to be illustrative, not limiting. Various changes may be made without departing from the spirit and scope of the invention as defined in the following claims.

The invention claimed is:

1. A coaxial cable connector comprising:
a body having an outer body surface and a forward facing body surface;
a post having a rearward facing post surface and configured to be separate from the body;
a coupler having a forward facing coupler surface, a first rearward facing coupler surface, a second rearward facing coupler surface, and an inner coupler surface extending along an axial direction between the first and second rearward facing coupler surfaces, the forward facing coupler surface configured to engage the rearward facing post surface when the connector is in an assembled state, the first rearward facing coupler surface being spaced axially rearward from the second rearward facing coupler surface when the connector is in the assembled state;
a coupler-body metallic continuity ground path extending between the coupler and the body when the connector is in the assembled state and when the coupler and body move relative to one another, the coupler-body metallic continuity ground path being located outside the inner coupler surface and outside the body such that no portion of the coupler-body metallic continuity ground path is located either inside the body or inside the first rearward facing coupler surface when the connector is in the assembled state;
a sealing member configured to form a seal between the inner coupler surface and the body, the seal being located axially forward from at least part of the coupler-body metallic continuity ground path when the connector is in the assembled state;
wherein the coupler-body metallic continuity ground path does not extend to the second rearward facing coupler surface;
wherein the coupler-body metallic continuity ground path extends around and outside of a section of the body when the connector is in the assembled state;
wherein the coupler is configured to move between a first position, where the coupler-body metallic continuity ground path extends through the first rearward facing coupler surface and where the second rearward facing coupler surface does not engage the forward facing body surface, and a second position, where the coupler-body metallic continuity ground path maintains contact with the first rearward facing coupler surface and where the second rearward facing coupler surface engages the forward facing body surface;
wherein the sealing member comprises an O-ring;
wherein the body extends inside the inner coupler surface when the connector is in the assembled state; and
wherein the body, the post, and the coupler each comprise separate and distinct structures.
  2. The coaxial cable connector of claim 1, wherein the body and the post do not comprise a single integral component.
3. The coaxial cable connector of claim 1, wherein the body and the post are configured to be interlocked together when assembled.
  4. The coaxial cable connector of claim 1, wherein the first rearward facing coupler surface comprises a continuity engaging portion.
  5. The coaxial cable connector of claim 1, wherein the first rearward facing coupler surface comprises a radial surface.
  6. The coaxial cable connector of claim 5, wherein the radial surface is configured to face an end of the connector when the connector is in the assembled state.
  7. The coaxial cable connector of claim 5, wherein the radial surface is not configured to face an end of the coupler.
  8. The coaxial cable connector of claim 5, wherein the radial surface comprises a radial end-most surface of the coupler.
  9. The coaxial cable connector of claim 5, wherein the radial surface radially extends outward from the inner coupler surface.
  10. The coaxial cable connector of claim 1, wherein the first rearward facing coupler surface radially extends outward from the inner coupler surface.
  11. The coaxial cable connector of claim 1, wherein the first rearward facing coupler surface is axially spaced rearward from a portion of the inner coupler surface.
  12. The coaxial cable connector of claim 1, wherein the inner coupler surface is located inside the coupler.
  13. The coaxial cable connector of claim 1, wherein the inner coupler surface is located proximate to an edge of the coupler.
  14. The coaxial cable connector of claim 1, wherein the inner coupler surface faces an inward direction.
  15. The coaxial cable connector of claim 1, wherein the inner coupler surface is located axially forward from a portion of the first rearward facing coupler surface.
  16. The coaxial cable connector of claim 1, wherein the inner coupler surface is located radially inward from a portion of the first rearward facing coupler surface.
  17. The coaxial cable connector of claim 1, wherein the inner coupler surface faces an inward direction, extends from the first rearward facing coupler surface, and the first rearward facing coupler surface faces a rearward direction.
  18. The coaxial cable connector of claim 1, wherein the first rearward facing coupler surface comprises an outer surface.
  19. The coaxial cable connector of claim 1, wherein the first rearward facing coupler surface comprises an outer annular surface.
  20. The coaxial cable connector of claim 1, wherein first rearward facing coupler surface is cylindrically shaped.
  21. The coaxial cable connector of claim 1, wherein the outer body surface does not include a forward end of the body.
  22. The coaxial cable connector of claim 1, wherein the outer body surface is located proximate to a forward end of the body.
  23. The coaxial cable connector of claim 1, wherein the body includes a forward body end, and the outer body surface and the forward body end comprise separate and distinct portions of the body.
  24. The coaxial cable connector of claim 1, further comprising a metal continuity member configured to maintain the coupler-body metallic continuity ground path extending between the coupler and the body even when the coupler is in a loose state.
  25. The coaxial cable connector of claim 1, wherein the axial direction comprises a general direction of a main axis of the connector.

26. The coaxial cable connector of claim 1, wherein the axial direction is not perfectly parallel to a main axis of the connector.

27. A coaxial cable connector comprising:

a body having an outer body surface and a forward facing body surface;
a post having a rearward facing post surface and configured to be separate from the body;
a coupler having a forward facing coupler surface, a first rearward facing coupler surface, a second rearward facing coupler surface, and an inner coupler surface extending along an axial direction between the first and second rearward facing coupler surfaces, the forward facing coupler surface configured to engage the rearward facing post surface when the connector is in an assembled state, the first rearward facing coupler surface being spaced axially rearward from the second rearward facing coupler surface when the connector is in the assembled state; and
a coupler-body metallic continuity ground path extending between the first rearward facing coupler surface and the outer body surface when the connector is in the assembled state and when the coupler and body move relative to one another, the coupler-body metallic continuity ground path being located outside the inner coupler surface, around a portion of the body, and so as to at least partially encircle a portion of the post such that no portion of the coupler-body metallic continuity ground path is located either inside the body or inside the first rearward facing coupler surface when the connector is in the assembled state.

28. The coaxial cable connector of claim 27, further comprising a sealing member configured to form a seal between the inner coupler surface and the body, the seal being located axially forward from at least part of the coupler-body metallic continuity ground path when the connector is in the assembled state.

29. The coaxial cable connector of claim 27, wherein the coupler-body metallic continuity ground path does not extend to the second rearward facing coupler surface when the connector is in the assembled state.

30. The coaxial cable connector of claim 27, wherein the coupler is configured to move between a first position, where the coupler-body metallic continuity ground path extends to the first rearward facing coupler surface and where the second rearward facing coupler surface does not engage the forward facing body surface, and a second position, where the coupler-body metallic continuity ground path extends to the first rearward facing coupler surface and where the second rearward facing coupler surface contacts the forward facing body surface.

31. The coaxial cable connector of claim 27, wherein the coupler-body metallic continuity ground path is C-shaped.

32. The coaxial cable connector of claim 28, wherein the sealing member comprises an O-ring.

33. The coaxial cable connector of claim 27, wherein a portion of the body extends inside the inner coupler surface when the connector is in the assembled state.

34. The coaxial cable connector of claim 27, wherein the body, the post, and the coupler each comprise separate and distinct structures.

35. The coaxial cable connector of claim 27, wherein the body and the post do not comprise a single integral component.

36. The coaxial cable connector of claim 27, wherein the body and the post are configured to be interlocked together when assembled.

37. The coaxial cable connector of claim 27, wherein the first rearward facing coupler surface comprises a continuity engaging portion.

38. The coaxial cable connector of claim 27, wherein the first rearward facing coupler surface comprises a radial surface.

39. The coaxial cable connector of claim 38, wherein the radial surface is configured to face an end of the connector when the connector is in the assembled state.

40. The coaxial cable connector of claim 38, wherein the radial surface is not configured to face an end of the coupler.

41. The coaxial cable connector of claim 38, wherein the radial surface comprises a radial end-most surface of the coupler.

42. The coaxial cable connector of claim 38, wherein the radial surface radially extends outward from the inner coupler surface.

43. The coaxial cable connector of claim 27, wherein the first rearward facing coupler surface radially extends outward from the inner coupler surface.

44. The coaxial cable connector of claim 27, wherein the first rearward facing coupler surface is axially spaced rearward from a portion of the inner coupler surface.

45. The coaxial cable connector of claim 27, wherein the inner coupler surface is located inside the coupler.

46. The coaxial cable connector of claim 27, wherein the inner coupler surface is located proximate to an edge of the coupler.

47. The coaxial cable connector of claim 27, wherein the inner coupler surface faces an inward direction.

48. The coaxial cable connector of claim 27, wherein the inner coupler surface is located axially forward from a portion of the first rearward facing coupler surface.

49. The coaxial cable connector of claim 27, wherein the inner coupler surface is located radially inward from a portion of the first rearward facing coupler surface.

50. The coaxial cable connector of claim 27, wherein the inner coupler surface faces an inward direction, extends from the first rearward facing coupler surface, and the first rearward facing coupler surface faces a rearward direction.

51. The coaxial cable connector of claim 27, wherein the first rearward facing coupler surface comprises an outer surface.

52. The coaxial cable connector of claim 27, wherein the first rearward facing coupler surface comprises an outer annular surface.

53. The coaxial cable connector of claim 27, wherein first rearward facing coupler surface is cylindrically shaped.

54. The coaxial cable connector of claim 27, wherein the outer body surface does not include a forward end of the body.

55. The coaxial cable connector of claim 27, wherein the outer body surface is located proximate to a forward end of the body.

56. The coaxial cable connector of claim 27, wherein the body includes a forward body end, and the outer body surface and the forward body end comprise separate and distinct portions of the body.

57. The coaxial cable connector of claim 27, further comprising a metal continuity member configured to maintain the coupler-body metallic continuity ground path extending between the coupler and the body even when the coupler is in a loose state.

58. The coaxial cable connector of claim 27, wherein the axial direction comprises a general direction of a main axis of the connector.

21

59. The coaxial cable connector of claim 27, wherein the axial direction is not perfectly parallel to a main axis of the connector.

60. The coaxial cable connector of claim 57, wherein the body and the post do not comprise a single integral component.

61. The coaxial cable connector of claim 57, wherein the body and the post are configured to be interlocked together when assembled.

62. The coaxial cable connector of claim 60, wherein the first rearward facing coupler surface comprises a continuity engaging portion.

63. The coaxial cable connector of claim 62, wherein the first rearward facing coupler surface comprises a radial surface.

64. The coaxial cable connector of claim 63, wherein the radial surface is configured to face an end of the connector when the connector is in the assembled state.

65. The coaxial cable connector of claim 63, wherein the radial surface is not configured to face an end of the coupler.

66. The coaxial cable connector of claim 64, wherein the radial surface comprises a radial end-most surface of the coupler.

67. The coaxial cable connector of claim 64, wherein the radial surface radially extends outward from the inner coupler surface.

68. The coaxial cable connector of claim 60, wherein the first rearward facing coupler surface radially extends outward from the inner coupler surface.

69. The coaxial cable connector of claim 68, wherein the first rearward facing coupler surface is axially spaced rearward from a portion of the inner coupler surface.

70. The coaxial cable connector of claim 69, wherein the inner coupler surface is located inside the coupler.

71. The coaxial cable connector of claim 70, wherein the inner coupler surface is located proximate to an edge of the coupler.

72. The coaxial cable connector of claim 71, wherein the inner coupler surface faces an inward direction.

73. The coaxial cable connector of claim 72, wherein the inner coupler surface is located axially forward from a portion of the first rearward facing coupler surface.

74. The coaxial cable connector of claim 60, wherein the inner coupler surface is located radially inward from a portion of the first rearward facing coupler surface.

75. The coaxial cable connector of claim 74, wherein the inner coupler surface faces an inward direction, extends from the first rearward facing coupler surface, and the first rearward facing coupler surface faces a rearward direction.

76. The coaxial cable connector of claim 75, wherein the first rearward facing coupler surface comprises an outer surface.

77. The coaxial cable connector of claim 76, wherein the first rearward facing coupler surface comprises an outer annular surface.

78. The coaxial cable connector of claim 77, wherein first rearward facing coupler surface is cylindrically shaped.

79. The coaxial cable connector of claim 78, wherein the outer body surface does not include a forward end of the body.

80. The coaxial cable connector of claim 79, wherein the outer body surface is located proximate to a forward end of the body.

81. The coaxial cable connector of claim 80, wherein the body includes a forward body end, and the outer body surface and the forward body end comprise separate and distinct portions of the body.

22

82. The coaxial cable connector of claim 30, further comprising a metal continuity member configured to maintain the coupler-body metallic continuity ground path extending between the coupler and the body even when the coupler is in a loose state.

83. The coaxial cable connector of claim 82, wherein the axial direction comprises a general direction of a main axis of the connector.

84. The coaxial cable connector of claim 82, wherein the axial direction is not perfectly parallel to a main axis of the connector.

85. The coaxial cable connector of claim 27, wherein the body, the post, and the coupler each comprise separate and distinct structures.

86. A coaxial cable connector comprising:
a body having an outer body surface and a forward facing body surface;

a post having a rearward facing post surface and configured to be separate from the body;
a coupler having a forward facing coupler surface, a first rearward facing coupler surface, a second rearward facing coupler surface, and an inner coupler surface extending along an axial direction between the first and second rearward facing coupler surfaces, the forward facing coupler surface configured to engage the rearward facing post surface when the connector is in an assembled state, the first rearward facing coupler surface being spaced axially rearward from the second rearward facing coupler surface when the connector is in the assembled state;

a coupler-body metallic continuity ground path extending between the first rearward facing coupler surface and the outer body surface when the connector is in the assembled state and when the coupler and body move relative to one another, the coupler-body metallic continuity ground path being located outside the inner coupler surface, around a portion of the body, and so as to at least partially encircle a portion of the post such that no portion of the coupler-body metallic continuity ground path is located either inside the body or inside the first rearward facing coupler surface when the connector is in the assembled state; and

a sealing member configured to form a seal between the inner coupler surface and the body, the seal being located axially forward from at least part of the coupler-body metallic continuity ground path when the connector is in the assembled state; and

wherein the coupler is configured to move between a first position, where the coupler-body metallic continuity ground path extends to the first rearward facing coupler surface and where the second rearward facing coupler surface does not engage the forward facing body surface, and a second position, where the coupler-body metallic continuity ground path extends to the first rearward facing coupler surface and where the second rearward facing coupler surface contacts the forward facing body surface.

87. The coaxial cable connector of claim 86, wherein the coupler-body metallic continuity ground path does not extend to the second rearward facing coupler surface when the connector is in the assembled state.

88. The coaxial cable connector of claim 86, wherein the coupler-body metallic continuity ground path is C-shaped.

89. The coaxial cable connector of claim 86, wherein the sealing member comprises an O-ring.

90. The coaxial cable connector of claim 86, wherein a portion of the body extends inside the inner coupler surface when the connector is in the assembled state.

91. The coaxial cable connector of claim 86, wherein the body, the post, and the coupler each comprise separate and distinct structures.

92. The coaxial cable connector of claim 86, wherein the body and the post do not comprise a single integral component.

93. The coaxial cable connector of claim 86, wherein the body and the post are configured to be interlocked together when assembled.

94. The coaxial cable connector of claim 86, wherein the first rearward facing coupler surface comprises a continuity engaging portion.

95. The coaxial cable connector of claim 86, wherein the first rearward facing coupler surface comprises a radial surface.

96. The coaxial cable connector of claim 95, wherein the radial surface is configured to face an end of the connector when the connector is in the assembled state.

97. The coaxial cable connector of claim 95, wherein the radial surface comprises a radial end-most surface of the coupler.

98. The coaxial cable connector of claim 95, wherein the radial surface radially extends outward from the inner coupler surface.

99. The coaxial cable connector of claim 86, wherein the first rearward facing coupler surface radially extends outward from the inner coupler surface.

100. The coaxial cable connector of claim 86, wherein the first rearward facing coupler surface is axially spaced rearward from a portion of the inner coupler surface.

101. The coaxial cable connector of claim 86, wherein the inner coupler surface is located inside the coupler.

102. The coaxial cable connector of claim 86, wherein the inner coupler surface faces an inward direction.

103. The coaxial cable connector of claim 86, wherein the inner coupler surface is located axially forward from a portion of the first rearward facing coupler surface.

104. The coaxial cable connector of claim 86, wherein the inner coupler surface is located radially inward from a portion of the first rearward facing coupler surface.

105. The coaxial cable connector of claim 86, wherein the inner coupler surface faces an inward direction, extends from the first rearward facing coupler surface, and the first rearward facing coupler surface faces a rearward direction.

106. The coaxial cable connector of claim 86, wherein the first rearward facing coupler surface comprises an outer annular surface.

107. The coaxial cable connector of claim 86, wherein the outer body surface does not include a forward end of the body.

108. The coaxial cable connector of claim 86, wherein the body includes a forward body end, and the outer body surface and the forward body end comprise separate and distinct portions of the body.

109. The coaxial cable connector of claim 86, further comprising a metal continuity member configured to maintain the coupler-body metallic continuity ground path extending between the coupler and the body even when the coupler is in a loose state.

110. The coaxial cable connector of claim 86, wherein the axial direction comprises a general direction of a main axis of the connector.

111. The coaxial cable connector of claim 86, wherein the axial direction is not perfectly parallel to a main axis of the connector.

112. A coaxial cable connector comprising:
a body having an outer body surface and a forward facing body surface;

a post having a rearward facing post surface and configured to be separate from the body;

a coupler having a forward facing coupler surface, a first rearward facing coupler surface, a second rearward facing coupler surface, and an inner coupler surface extending along an axial direction between the first and second rearward facing coupler surfaces, the forward facing coupler surface configured to engage the rearward facing post surface when the connector is in an assembled state, the first rearward facing coupler surface being spaced axially rearward from the second rearward facing coupler surface when the connector is in the assembled state;

a coupler-body metallic continuity ground path extending between the first rearward facing coupler surface and the outer body surface when the connector is in the assembled state and when the coupler and body move relative to one another, the coupler-body metallic continuity ground path being located outside the inner coupler surface, around a portion of the body, and so as to at least partially encircle a portion of the post such that no portion of the coupler-body metallic continuity ground path is located either inside the body or inside the first rearward facing coupler surface when the connector is in the assembled state; and

wherein the coupler is configured to move between a first position, where the coupler-body metallic continuity ground path extends to the first rearward facing coupler surface and where the second rearward facing coupler surface does not engage the forward facing body surface, and a second position, where the coupler-body metallic continuity ground path extends to the first rearward facing coupler surface and where the second rearward facing coupler surface contacts the forward facing body surface.

113. The coaxial cable connector of claim 112, further comprising a sealing member configured to form a seal between the inner coupler surface and the body, the seal being located axially forward from at least part of a continuity member when the connector is in the assembled state.

114. The coaxial cable connector of claim 112, wherein the coupler-body metallic continuity ground path does not contact the second rearward facing coupler surface when the connector is in the assembled state.

115. The coaxial cable connector of claim 112, wherein the coupler-body metallic continuity ground path is C-shaped.

116. The coaxial cable connector of claim 113, wherein the sealing member comprises an O-ring.

117. The coaxial cable connector of claim 112, wherein a portion of the body extends inside the inner coupler surface when the connector is in the assembled state.

118. The coaxial cable connector of claim 112, wherein the body and the post do not comprise a single integral component.

119. The coaxial cable connector of claim 112, wherein the body and the post are configured to be interlocked together when assembled.

120. The coaxial cable connector of claim 112, wherein the first rearward facing coupler surface comprises a continuity engaging portion.

121. The coaxial cable connector of claim 112, wherein the first rearward facing coupler surface comprises a radial surface.

122. The coaxial cable connector of claim 121, wherein the radial surface is configured to face an end of the connector when the connector is in the assembled state.

123. The coaxial cable connector of claim 121, wherein the radial surface comprises a radial end-most surface of the coupler. 5

124. The coaxial cable connector of claim 121, wherein the radial surface radially extends outward from the inner coupler surface. 10

125. The coaxial cable connector of claim 112, wherein the first rearward facing coupler surface radially extends outward from the inner coupler surface. 10

126. The coaxial cable connector of claim 112, wherein the first rearward facing coupler surface is axially spaced rearward from a portion of the inner coupler surface. 15

127. The coaxial cable connector of claim 112, wherein the inner coupler surface is located inside the coupler. 15

128. The coaxial cable connector of claim 112, wherein the inner coupler surface faces an inward direction. 20

129. The coaxial cable connector of claim 112, wherein the inner coupler surface is located axially forward from a portion of the first rearward facing coupler surface. 20

130. The coaxial cable connector of claim 112, wherein the inner coupler surface is located radially inward from a portion of the first rearward facing coupler surface. 25

131. The coaxial cable connector of claim 112, wherein the inner coupler surface faces an inward direction, extends from the first rearward facing coupler surface, and the first rearward facing coupler surface faces a rearward direction. 25

132. The coaxial cable connector of claim 112, wherein the first rearward facing coupler surface comprises an outer annular surface. 30

133. The coaxial cable connector of claim 112, wherein the outer body surface does not include a forward end of the body. 30

134. The coaxial cable connector of claim 112, wherein the body includes a forward body end, and the outer body surface and the forward body end comprise separate and distinct portions of the body. 35

135. The coaxial cable connector of claim 112, further comprising a metal continuity member configured to maintain the coupler-body metallic continuity ground path extending between the coupler and the body even when the coupler is in a loose state. 40

136. The coaxial cable connector of claim 112, wherein the axial direction comprises a general direction of a main axis of the connector. 45

137. The coaxial cable connector of claim 112, wherein the axial direction is not perfectly parallel to a main axis of the connector. 50

138. A coaxial cable connector comprising:

a body having an outer body surface and a forward facing body surface;

a post having a rearward facing post surface and configured to be separate from the body;

a coupler having a forward facing coupler surface, a first rearward facing coupler surface, a second rearward facing coupler surface, and an inner coupler surface extending along an axial direction between the first and second rearward facing coupler surfaces, the forward facing coupler surface configured to engage the rearward facing post surface when the connector is in an assembled state, the first rearward facing coupler surface being spaced axially rearward from the second rearward facing coupler surface when the connector is in the assembled state; 55

a coupler-body metallic continuity ground path configured to extend between the first rearward facing coupler sur-

face and the outer body surface when the connector is in the assembled state and when the coupler and body move relative to one another, the coupler-body metallic continuity ground path being located outside the inner coupler surface, around a portion of the body, and being located so as to at least partially encircle a portion of the post such that no portion of the coupler-body metallic continuity ground path is located either inside the body or inside the first rearward facing coupler surface when the connector is in the assembled state; and

wherein a portion of the body extends inside the inner coupler surface when the connector is in the assembled state.

139. The coaxial cable connector of claim 138, further comprising a sealing member configured to form a seal between the inner coupler surface and the body, the seal being located axially forward from at least part of the coupler-body metallic continuity ground path when the connector is in the assembled state. 15

140. The coaxial cable connector of claim 138, wherein the coupler-body metallic continuity ground path does not contact the second rearward facing coupler surface when the connector is in the assembled state. 20

141. The coaxial cable connector of claim 138, wherein the coupler is configured to move between a first position, where the coupler-body metallic continuity ground path extends to the first rearward facing coupler surface and where the second rearward facing coupler surface does not engage the forward facing body surface, and a second position, where the coupler-body metallic continuity ground path extends to the first rearward facing coupler surface and where the second rearward facing coupler surface contacts the forward facing body surface. 25

142. The coaxial cable connector of claim 138, wherein the coupler-body metallic continuity ground path is C-shaped. 30

143. The coaxial cable connector of claim 139, wherein the sealing member comprises an O-ring. 35

144. The coaxial cable connector of claim 138, wherein the body, the post, and the coupler each comprise separate and distinct structures. 40

145. The coaxial cable connector of claim 138, wherein the body and the post do not comprise a single integral component. 45

146. The coaxial cable connector of claim 138, wherein the body and the post are configured to be interlocked together when assembled. 50

147. The coaxial cable connector of claim 138, wherein the first rearward facing coupler surface comprises a continuity engaging portion. 55

148. The coaxial cable connector of claim 138, wherein the first rearward facing coupler surface comprises a radial surface. 60

149. The coaxial cable connector of claim 148, wherein the radial surface is configured to face an end of the connector when the connector is in the assembled state. 65

150. The coaxial cable connector of claim 148, wherein the radial surface comprises a radial end-most surface of the coupler. 70

151. The coaxial cable connector of claim 148, wherein the radial surface radially extends outward from the inner coupler surface. 75

152. The coaxial cable connector of claim 138, wherein the first rearward facing coupler surface radially extends outward from the inner coupler surface. 80

153. The coaxial cable connector of claim 138, wherein the first rearward facing coupler surface is axially spaced rearward from a portion of the inner coupler surface. 85

154. The coaxial cable connector of claim 138, wherein the inner coupler surface is located inside the coupler.

155. The coaxial cable connector of claim 138, wherein the inner coupler surface faces an inward direction.

156. The coaxial cable connector of claim 138, wherein the inner coupler surface is located axially forward from a portion of the first rearward facing coupler surface.

157. The coaxial cable connector of claim 138, wherein the inner coupler surface is located radially inward from a portion of the first rearward facing coupler surface.

158. The coaxial cable connector of claim 138, wherein the inner coupler surface faces an inward direction, extends from the first rearward facing coupler surface, and the first rearward facing coupler surface faces a rearward direction.

159. The coaxial cable connector of claim 138, wherein the first rearward facing coupler surface comprises an outer annular surface.

160. The coaxial cable connector of claim 138, wherein the outer body surface does not include a forward end of the body.

161. The coaxial cable connector of claim 138, wherein the body includes a forward body end, and the outer body surface and the forward body end comprise separate and distinct portions of the body.

162. The coaxial cable connector of claim 138, further comprising a metal continuity member configured to maintain the coupler-body metallic continuity ground path extending between the coupler and the body even when the coupler is in a loose state.

163. The coaxial cable connector of claim 138, wherein the axial direction comprises a general direction of a main axis of the connector.

164. The coaxial cable connector of claim 138, wherein the axial direction is not perfectly parallel to a main axis of the connector.
